Application June 4, 1949, Serial No. 97,161

7 Claims. (Cl. 228—59)

1

This invention relates to a ladder adapted to extend, either in itself or by a movable prolongation, to considerable height. One of the objects of the invention is to provide suitable bracing trusses for longitudinal rails of the ladder, so that the ladder may have sufficient strength and stiffness without undue weight. Another feature relates to the rungs of the ladder, the object being to provide such members in the form of low cost which may be readily replaced from time to time if they become distorted.

My invention is illustrated in the drawings hereof and is hereinafter more fully explained and the essential novel features set out in the claims.

In the drawings, Fig. 1 is a side elevation of my ladder equipped with an extended portion embodying the same trussing and rung features; Fig. 2 is a cross section of the ladder indicated by the line 2—2 of Fig. 1; Fig. 3 is a fragmentary side elevation of the ladder looking at the strut of Fig. 2, as indicated by the line 3—3 on Fig. 2; Figs. 4 and 5 are details on correspondingly numbered lines on Fig. 3; Fig. 6 is a fragmentary view of the ladder showing particularly the rungs and their attachment to the longitudinal rails; Fig. 7 is an enlarged view of one of the rung attachments, being in the nature of a fragmentary elevation indicated by the line 7—7 on Fig. 3; Fig. 8 is an axial section through a portion of a rung, showing its mounting, the position being indicated by the line 8—8 on Fig. 7; Fig. 9 is a view of a portion of one of the rungs and of one of its mountings, as indicated by the line 9—9 on Fig. 8 looking upwardly.

In the drawings, 10 indicates one of the two rails or longitudinal bars of my ladder carrying suitable rungs 30. Fig. 1 shows at 11 the rails of an extension of the ladder 10 suitably mounted thereon and projecting above it. Each of the rails 10 and 11 is braced by a truss of this invention which stiffens and strengthens the same and avoids unduly heavy material for the rails.

The trussing comprises a pair of upright struts 12 secured to each of the rails 10 and 11 and suitable tension bars 13, 14 and 15 resting on and anchored to said struts. Each of the struts 12 has a fork 12a at its upper end and the opposite wings of this fork are bifurcated by downwardly extending notches, so that the fork in effect presents four upstanding prongs spaced at the four corners of the horizontal rectangle. The tension bars 14 and 15 are secured at their far ends to the ladder by reason of passing through a bracket 16 or a doubled ear on a

5 bracket 17 extending across the end of the rail and onto the upper and underside thereof. On these rods 14 and 15 beyond the brackets are threaded nuts. At the other end of the rods each rod is threaded into a transverse pin 18 which occupies the notches in the fork 12a at the head of the strut 12.

Between the two struts 12 is the rod 13, the 10 end portions of which are threaded into transverse pins 19 which also lie in the notches of the fork 12a of the strut. The rods are held in the fork by suitable transverse pins 20 extending through the arms 12a above the rod 13.

Between the two struts 12 is the rod 13, the 15 end portions of which are threaded into transverse pins 19 which also lie in the notches of the fork 12a of the strut. The rods are held in the fork by suitable transverse pins 20 extending through the arms 12a above the rod 13.

20 The upright struts 12 are shown as being made rigid with angle brackets 21 at their lower ends which brackets extend onto the outer face of the rail 10 or the inner face of the rail 11 and overhang the top of such rail. These brackets are 25 secured in place by bolts 22 extending through the bracket and rail. In Figs. 1, 2 and 3, I have indicated the lower part of the rail 10 as reinforced by a channel-shaped metal member 23 on its outer face and overlapping at its upper 30 and lower edges.

It will be seen that the construction described provides thoroughly stiffened rails 10 of the main ladder or those 11 of the extension. The struts 12 extend upwardly from the outer side 35 of the rails 10 and then are bent inwardly, or they extend from the inner side of the extension rails 11 and are then bent outwardly, so that in either case the tension rods come directly over the rails.

40 I have shown in Fig. 1 a suitable standard 26 for carrying the ladder described, the ladder being pivoted to this standard on an axis indicated at 27. Suitable mechanism not shown 45 mounted on the ladder 10 and the extension 11 serves to project that extension as desired. I have indicated in Fig. 1 a suitable hand wheel 28 for operating the extending mechanism. This view shows also a telescopic tie 29 connecting the standard 26 with an ear 10a on the ladder and operable by suitable mechanism not shown for tipping the ladder on its pivot. The ladder support, the tipping mechanism and the extension means, however, are no part of the present invention.

55 Between the two rails 10 or 11 on the ladder

or its extension are suitable rungs 30. These rungs are metal tubes, the end portions of which occupy openings in the rails. On the outer side of the ladder I provide stopping plates 31 which are abutted by the ends of the rungs. The rungs carry diametric pins 35 which when the rungs are in place abut the inner surface of the rails. Suitable collars 36 surround the rungs on the inner face of the rails and overhang the diametric pins 35 and abut the inner face of the rails, as shown in Fig. 8. The collars are formed as shown in Figs. 8 and 9 and have cylindrical portions snugly surrounding the rungs, and recessed intermediate portions to house the ends of the pins 35, and finally flat flanged portions to engage the rail face. Suitable cross bolts 37 extend through the outer plates through the rails and through the collars 36 and carry nuts 39 on their ends, securing all of the parts in place.

The provision of the removable collars 36 and the rungs carrying the cross pins 35 retained in place by those collars, provides very ready means whereby a bent or distorted rung may be replaced by a fresh rung. The removal of the nuts 39 allows the removal of the collar 36, thus freeing the diametric pin 35 so that it may be driven out of the rung. The freed bolts 37 may also be withdrawn from the rail, which frees the plate 31. Accordingly, any rung may be moved outwardly through the rail its end portion normally occupies.

It will be seen that by the provision of rungs and the provision for bracing the rails of the ladder I have provided a structure adapted for economic construction and ready assemblage. The trussing of the rails allows them to be materially lighter than otherwise permissible. The adjustable anchorages for the ends of the tie rods enables the rods to be given the desired tension in their seats. Any distortion of the parts from use may be readily remedied.

40 indicates insulators mounted on the rods 13. I prefer to use one of these on each of these rods. These insulators may be slideable along the rods and thus available for the operator as he mounts the ladder, and they serve to protect him from shock if the upper end of the ladder should inadvertently encounter a charged conductor.

The claims of the present application are directed to the claims on the reinforced ladder construction. Claims directed to the construction of the joint between the rung and rail are presented in my divisional application, Serial No. 147,274, filed March 2, 1950.

I claim:

1. In a ladder, the combination of a rail, a strut secured thereto and projecting therefrom, a fork at the free end of said strut having wings in the plane of said rail, aligning notches through both wings of said fork, and a tension rod secured at one end to the rail and at the other end having a cross pin occupying said notches.

2. In a ladder, the combination with a pair of rails and suitable rungs connecting them, of a pair of trusses for the two rails respectively, each truss comprising a strut secured to the rail and projecting therefrom and having thereon a forked end transverse to said rail, each wing of the fork being bifurcated, two tension rods having transverse pins at their adjacent ends, both of said rods occupying the fork of the strut and both of

said pins occupying the crotch of the bifurcated wings.

3. In a ladder, the combination with one of the rails of a strut secured thereto, said strut having a forked end transverse to said rail with notches in its two side members, and a tension rod anchored at one end to means carried by the rail and at the other end threaded into a projecting cross pin, said rod extending between the side members of said fork and having its pin occupying the notches of the fork.

4. In a ladder, the combination with the rails, of a strut having at one end a bracket resting against the edge and side of a rail and secured thereto, said strut having a forked free end transverse to said rail with notches in its two side wings, and a pair of tension rods each having a projecting cross pin, said rods extending between the arms of said fork and having their pins occupying the notches of the fork.

5. In a ladder, the combination of a pair of rails and rungs between them, a pair of struts secured to each rail, each strut having a fork at its free end transverse to said rails which fork has transverse notches in its arms, inclined rods anchored at opposite ends to the end portions of the rail, said rods carrying cross pins occupying the notches of the adjacent struts, and a tension rod substantially parallel with the rail and having cross pins at its opposite ends also occupying the notches of the struts.

6. In a ladder, the combination of a rail, a strut secured thereto and projecting therefrom, a fork transverse to said rails at the free end of said strut, aligning notches through both arms of said fork, a pair of tension rods secured at their distant ends to means carried by the rail, said rods at their adjacent ends each having a cross pin occupying said notches, the rod having threads and each threaded in a passage in the cross pin, the cross pins occupying the notches of the strut when the rods occupy the space between the fork arms, and transverse pins extending through and secured to the arms of said fork on either side of the notch for holding the rods and cross pins therein.

7. In a ladder, the combination of a rail, a strut secured thereto and projecting therefrom, a four-pronged fork mounted on the free end of said strut forming intersecting aligned notches between the corresponding prongs, one of said notches being parallel and the other of said notches being transverse to the rails respectively, and a tension rod secured at one end of the rail and at the other end having a cross pin occupying said transverse notches.
